UNITED STATES PATENT OFFICE.

JAMES GREENWOOD, OF LONDON, ENGLAND.

PROCESS AND APPARATUS FOR THE ELECTROLYTIC DECOMPOSITION OF ALKALINE SALTS.

984,905.

Specification of Letters Patent. Patented Feb. 21, 1911.

Application filed November 22, 1909. Serial No. 529,442.

To all whom it may concern:

Be it known that I, JAMES GREENWOOD, a subject of the King of England, residing at London, England, have invented a certain new and useful Improved Process and Apparatus for the Electrolytic Decomposition of Alkaline Salts, of which the following is a specification.

This invention relates to improvements in the electrolytic decomposition of alkaline salts by the diaphragm method, chiefly for the production of caustic soda and caustic potash from sodium chlorid and potassium chlorid respectively; the object being to produce an electrolytic system which will work efficiently and economically even under the most variable conditions of electrical supply. To this end the method and apparatus are so devised as to enable the electrical resistance, the rate of flow of electrolyte, the percolation of electrolyte through the diaphragm and other factors to be readily controlled, as may be required.

According to this invention the resistance of an electrolytic cell is controlled in accordance with the current density employed by hermetically closing the cathode section except for the diaphragm and by reducing more or less the pressure in the cathode section, which is normally practically empty to regulate the rate of percolation of the electrolyte through the diaphragm.

A feature of this invention consists in the use of a cathode section hermetically closed and connected to a suction pump by means of which the necessary reduction of pressure can be effected and by which also the caustic liquor mixed with alkaline chlorid solution may be withdrawn from the cathode section.

According to this invention the anode, diaphragm, cathode, and casing of the cathode section are preferably in the form of concentric cones or V-shaped rectangular vessels, though they may be constructed in any suitable pyramidal form. Preferably the apparatus comprises a series of superimposed and concentric cells so arranged that the electrolyte flows from a hollow anode to the corresponding anode section (that is, the space between the hollow anode and the adjacent diaphragm member of the corresponding cathode), thence to the next hollow anode and into the corresponding anode

section and so on in cascade. With such an arrangement it is possible to regulate the flow of liquor into the first hollow anode and thereby through the whole apparatus, in accordance with the current density.

One method of carrying this invention into effect will now be described with reference to the accompanying drawings.

Figure 1 is a side elevation partly in section. Fig. 2 is a plan the cover of the apparatus and the uppermost anode being removed. Fig. 3 shows on an enlarged scale one of the cathode sections. Fig. 4 shows a side elevation partly in section of a modified form of apparatus, and Fig. 5 is an end elevation of the modified apparatus part of the casing being removed.

Like letters indicate like parts throughout the drawings.

The anode section of the first or upper cell contains a hollow anode A in the form of an inverted cone, constructed of ferro-silicon alloy or other material which effectively resists the electrolytic action at the anode. This anode has an outlet B at its apex.

The cathode section which is located immediately under the anode A is constructed as follows:—The inner member C consists of a porous vessel or diaphragm and the outer member C' is constructed from ebonite or other suitable material, and is provided with an internal annular projection C². Outside the diaphragm is a layer of asbestos cloth C³ surrounded by a layer of copper gauze C⁴, the latter forming the cathode proper. The application of the cathode, in the form of metallic gauze directly to the outer surface of the diaphragm is a well-known form of construction. A copper ring D' surrounds the top of the cathode and is metallically secured thereto, preferably by soldering. The ring D' is arranged to rest on the annular projection C² of the outer casing C' and to support the diaphragm C by a flange C⁵ on the latter resting on the top of the ring D'. Copper bolts H' are secured to the ring D' and project above the edge of the cathode section. The space surrounding the bolt and above the ring D' of the cathode section is filled in with any suitable cement. The bolts H' are further provided with nuts D² which

aid in securing the parts in position. Lugs D² are secured at intervals around the outer surface of the outer casing C' and form distance pieces and supports for the cathode section when in position in the underlying anode section as shown in Fig. 1. An ebonite tube E is provided in each cathode section the tubes E being all connected to a main pipe E' the latter being in communication with a vacuum effect apparatus or pump. Anode and cathode sections are arranged concentrically one below the other to the required number as illustrated in Fig. 1.

The apparatus is incased in a porcelain enameled iron or other suitable vessel or casing F mounted in a bed plate F' of slate or other non-conducting material and being closed at the top by a cover F². Through this cover a tube F³ conveys the alkaline salt solution which is to be decomposed to the upper anode section and another tube F⁴ is provided to carry off the chlorin gas which is evolved during the process.

Three columns G are supported in the base plate and are provided with projections G' which engage corresponding projections A' formed on the anode sections, thereby supporting the sections in place. These columns G form the positive terminals of the apparatus and in order to secure good electrical contact between the columns and the anodes, packing G² composed of sheets of soft lead is inserted between the projections A' and the projections G'.

Separate and insulated conductors H are carried through the bed plate F' and are connected separately to each of the extended copper bolts H' which form electrical contact by means of the copper ring D' with the cathode C⁴, which form the negative terminals of the apparatus. These conductors are carried to a specially constructed terminal outside the apparatus designed so that each cell can be tested separately as to its electrical condition. An outlet J is provided in the bed plate F' whereby the electrolyte finally passes away from the bottom section.

Figs. 4 and 5 illustrate a modified construction of apparatus. In place of the sections having conical formation they are constructed in V-form, that is to say, the apparatus is now provided with side walls K of slate, ebonite or other suitable material, and the anodes, diaphragms, cathodes and cathode sections and closing plates C' are cemented into grooves cut at an angle in the walls K. The cathode sections are inclosed by caps L at their upper ends and by cross bars L' at their lower ends. Portions of the anodes project beyond the edge of the side walls K and are provided with flanges A² to prevent the salt solution running over the edges and at the same time forming suitable terminals to connect the anode

plates to the electrical conductor G³ which leads to the positive terminal of the electrical supply.

The arrangement and operation of the apparatus is with the exception of the details described above similar to that of the conical construction.

The process of decomposing alkaline salts in the apparatus described is as follows: The solution of alkaline chlorid is introduced into the upper anode A through the conduit F³ which may be controlled by a suitable valve. As the anode sections are connected in cascade this valve can be operated to regulate the flow of the electrolyte liquor through the whole apparatus in accordance with the current density so that the electrolyte when leaving the cell can be maintained at a practically constant specific gravity; and so that the temperature may be regulated. The electrolyte having passed from the bottom of each hollow anode A into the anode section ascends therein and is subjected to the action of the electric current passing from the anode through the diaphragm C to the cathode C⁴ and at the same time the electrolyte percolates through the diaphragm, the rate of percolation being regulated by the vacuum in the cathode section according to the current density employed and caustic alkaline liquor is produced in the cathode section together with a certain proportion of alkali chlorid. This caustic alkaline liquor is removed through the suction conduit E'. By varying the degree of vacuum it is possible to regulate in the most exact manner the rate of percolation of the electrolyte through the diaphragm, and by this means the resistance of the cell can be regulated according to the variable current density. Thus when the current density is high, the vacuum in the cathode section is increased to a maximum, so as to permit a greater percolation through the diaphragm, and thereby produce a less resistance; and when the current density is low the vacuum is reduced correspondingly to diminish the percolation through the diaphragm. By this regulation of the percolation the products obtained from the cell are maintained at a constant strength and quality.

At electric power generating stations, the power actually utilized is generally less than 30% of the total generating capacity. The process and apparatus according to this invention are especially suitable for utilizing the variable surplus electric power amounting to over 70% of the total generating capacity. For this particular purpose, it is absolutely necessary that the electrolytic apparatus should work efficiently and economically even under the most variable conditions of electrical supply. At the same time it is desirable to maintain the voltage of the

electrolytic cells at substantially the same point, and also to obtain the products of electrolysis of approximately constant quality and strength. By the method above 5 described the resistance of the cells may be varied to fulfil these requirements. These conical or V-shaped rectangular cells can be built up vertically to any extent which may be required, thus obtaining an enormous 10 electrode and diaphragm surface within very small compass. This arrangement facilitates the automatic flow of the electrolyte, from cell to cell, by gravity, and at the same time allows the chlorin evolved in the anode 15 section to pass away freely. The partially exhausted electrolyte after passing through the series of cells is pumped back to be re-saturated with the alkali salt. The cost of this apparatus and erection is greatly reduced by this method of construction, which 20 can also be easily enlarged at any time, by increasing the number of cells in each apparatus as may be required.

The invention has been described in its 25 application to the production of caustic alkali from alkali chlorid but it is obvious that the process and apparatus may be adapted to the manufacture or production of other chemical products, the details of construction being capable of modification without departing from the spirit of the invention.

What I claim as my invention and desire 30 to secure by Letters Patent is:—

1. The hereinbefore described improvement in the method of electrolytically decomposing alkaline salts by the diaphragm process which consists in producing a partial 35 vacuum in the cathode section.

2. The hereinbefore described improvement in the method of electrolytically decomposing alkaline salts by the diaphragm process which consists in producing a partial 40 vacuum in the cathode section and maintaining said cathode section normally practically empty.

3. The hereinbefore described improvement in the method of electrolytically decomposing alkaline salts by the diaphragm 45 process which consists in closing the cathode section, producing a partial vacuum in said cathode section and maintaining it normally practically empty.

4. In the electrolytic decomposition of 50 alkaline salts by the diaphragm process, varying the rate of percolation of the electrolyte through the diaphragm by closing the cathode section which is normally practically empty and producing a partial vacuum therein.

5. In the electrolytic decomposition of 55 alkaline salts by the diaphragm process, the method of varying the resistance in accordance with the current density consisting in closing the cathode section and producing a

partial vacuum in such cathode section to alter the rate of percolation of the electrolyte through the diaphragm.

6. In the electrolytic decomposition of 60 alkaline salts by the diaphragm process, the herein described improvement consisting in closing the cathode section, producing a partial vacuum in said section, and withdrawing the caustic liquor by suction from the bottom of the cathode section.

7. In apparatus of the diaphragm type 65 the combination with a closed cathode section, of a suction pump connected with the interior of said section.

8. Apparatus for the electrolytic decomposition of alkaline salts by the diaphragm process in which the anode, diaphragm, cathode and casing of the cathode section are in the form of concentric pyramidal formations.

9. In apparatus for the decomposition of 70 alkaline salts by the diaphragm process, the combination with a cathode including a hollow diaphragm, of a hollow cone or pyramid-shaped anode extending into and providing between its outer surface and the cathode diaphragm a chamber through which electrolyte may flow, the anode having at its lower end an outlet communicating with said chamber.

10. Apparatus of the kind described, having a series of superimposed and concentric 75 cells so arranged that the electrolyte flows from the hollow anode to the corresponding anode section, thence to the next hollow anode and into the corresponding anode section and so on.

11. The herein described method of decomposing alkaline salts by electrolysis consisting in causing the liquor to pass through 80 a series of superimposed and concentric cells, each comprising a hollow anode and a cathode regulating the flow of liquor into the first hollow anode, and therefore through the whole apparatus in accordance 85 with the current density.

12. In apparatus of the kind described, the employment of cathode sections, each consisting of an outer pyramidal casing of 90 suitable material, an inner pyramidal member including a porous diaphragm, a metallic cathode surrounding the diaphragm, the space between the diaphragm and the outer casing being entirely closed.

13. An apparatus of the kind described 95 consisting of alternately arranged pyramidal anode and cathode sections placed one within the other, each cathode section forming an air-tight compartment, each anode section having an orifice at its apex so that the electrolyte can flow therefrom in cascade form from one anode to the other, and means for creating a partial vacuum in each cathode section.

14. In an apparatus of the character de- 100

scribed, the combination of a hollow anode, a cathode section adapted to receive the anode and comprising an inner porous diaphragm and an outer shell forming an inclosed chamber about the diaphragm and anode, and means for creating a partial vacuum in said chamber of the cathode.

In testimony whereof I have signed my name to this specification in the presence of two subscribing witnesses.
